[57] CLAIM

The ornamental design for a wall plate-bamboo, as shown and described.

DESCRIPTION

FIG. 1 is a perspective view of a wall plate for a switch illustrating our new design.

FIG. 2 is a front elevational view of the wall plate of FIG. 1.

FIG. 3 is a rear elevational view of the wall plate of FIG. 1.

FIG. 4 is an end plan view of the wall plate of FIG. 1.

FIG. 5 is a side elevational view of the wall plate as in FIG. 1.

FIG. 6 is a horizontal sectional view of the wall plate of FIG. 2 taken along the line 6—6 of FIG. 2.

FIG. 7 is a vertical sectional view of the wall plate of FIG. 2 taken along the line 7—7 of FIG. 2.

FIG. 8 is a vertical sectional view of a wall plate for a wall receptacle illustrating our new design, the surface decoration being shown only in patches for ease of illustration.

FIG. 9 is a vertical elevational view of a wall plate for two side-by-side switches illustrating our new design, the surface decoration being shown only in patches as in FIG. 8.
